Primary Examiner — Mark Goodwin*(74) Attorney, Agent, or Firm* — Leydig, Voit & Mayer, Ltd.(57) **CLAIM**

The ornamental design for a connection of two angled bus bars, as shown and described.

DESCRIPTION

FIG. 1 is an isometric view of a connection of two angled bus bars showing our new design, the broken line elements form no part of the claimed design;

FIG. 2 is a top view thereof;

FIG. 3 is a right side view thereof;

FIG. 4 is a left side view thereof;

FIG. 5 is a front view thereof;

FIG. 6 is a back view thereof;

FIG. 7 is an isometric view of a second embodiment of a connection of two angled bus bars showing our new design, the broken line elements form no part of the claimed design;

FIG. 8 is a top view thereof;

FIG. 9 is a right side view thereof;

FIG. 10 is a left side view thereof;

FIG. 11 is a front view thereof; and,

FIG. 12 is a back view thereof.

1 Claim, 8 Drawing Sheets---
